UNITED STATES PATENT OFFICE.

OTHO M. OTTE, OF JAMESTOWN, NEW YORK.

SHEET-METAL DOOR.

1,227,066.

Specification of Letters Patent. Patented May 22, 1917.

Application filed September 11, 1916. Serial No. 119,338.

To all whom it may concern:

Be it known that I, OTHO M. OTTE, a citizen of the United States, residing at the city of Jamestown, in the county of Chautauqua and State of New York, have invented certain new and useful Improvements in Sheet-Metal Doors, of which the following, taken in connection with the accompanying drawings, is a specification.

10 The invention relates to hollow sheet metal doors, and the object of the improvement is to provide a simply constructed, strong and durable door having molding decoration for the panels and stiles and
15 crossrails, which parts are strongly welded to and are braced by the panel piece; the corner construction between the tubular crossrails and stiles being strongly braced so that when the panel sheets are welded to
20 the outer frame of crossrails and stiles the entire door is rendered extremely rigid and durable and presents a fine appearance at low cost; and the invention consists in the novel features and combinations hereinafter
25 set forth and claimed.

25 set forth and claimed.
In the drawings, Figure 1 is a front elevation of the outer side of a door for a closet cabinet or other inclosure where a door having decoration on one side and not having
30 decoration on the other is desired. Fig. 2 is a sectional view at line X—X in Fig. 1 of a door decorated on one side. Fig. 3 is a sectional view of a modification of the hollow stile or crossrail and the edge of the
35 panel sheet showing decorative molding on both sides of the door, one side showing the sunken panel effect and the other side showing the flush panel effect. Fig. 4 is an elevation of a corner portion of the door showing
40 the manner of corner construction with the interior corner brace within the hollow ends of the mitered crossrail and stile shown in dotted outline; and Fig. 5 is a perspective view of said interior corner brace; and Fig.
45 6 is a sectional view at line Y—Y in Fig. 4 showing the close fit of the interior corner brace and how it supports the opposite sides of the hollow sheet metal crossrail and stile ends. Fig. 7 is a perspective sectional view
50 of a portion of the panel and the decorative molding shaped so as to be spot welded thereto.

Like characters of reference refer to corresponding parts in the several views.

The numeral 10 designates the stile; the 55 numeral 11 designates the crossrail; and the numeral 12 the panel sheet of the door.

The stiles 10 and crossrails 11 are formed in the hollow tubular shape, preferably rectangular, from strips of sheet metal by suitable dies, the lengthwise edges 13 being extended inward from the tubular portion of the crossrail or stile in a flange in which the two edges are placed evenly abutting upon one another and preferably in line with the inner side of the door and tubular portion. 60 65

The stiles 10 and crossrails 11 are joined at the corners by the mitered joint 14. In order to hold the ends of the stiles and cross-rails in this mitered relation, a slotted tubular internal brace 15 is provided in which the two wings 16 of the V-shaped corner brace 15 extend one into each end of the hollow stile and crossrail abutting at the line of the miter 14, which miter line 14 is also shown in Fig. 5 in dotted line on the corner brace 15. Each wing 16 of the corner brace 15 fits closely within its tubular end thereby supporting the side walls of the tubular ends a spaced distance apart and at the same time holding said tubular ends in the mitered relation. 70 75 80

The panel 12 is shaped to fit closely within the frame formed by the tubular stiles 10 and crossrails 11 so that the entire outer edge around the panel 12 may be spot welded through the abutting flanged edges 13 of the stile 10 and crossrail 11 thereby holding the mitered braced joints of the stiles and crossrails firmly in position attaching them to one another with close easily enameled, or otherwise finished joints, and rigidly holding all the parts in place. 15

When so welded the internal brace 15 fitting closely within the tubular corners, as shown in cross section in Fig. 6, braces the corner on all sides extending squarely across the mitered joint on one side thereby firmly supporting the mitered joint without need of welding or soldering attachment to the 100 ends of the stiles and cross-rails. The joint between the panel and the flange 13 is spot welded and takes a finish and makes a clean fine joint so that the inner edge of the stile and crossrail may be shaped in a molding 105 as shown at 17, thereby giving a fine panel effect without high cost.

When a greater decorative effect is desired, the

- sired a molding 18 is shaped with a portion 19 contiguous to the panel 12 when placed thereon so that the molding may be spot welded lengthwise along the portion 19, as shown in Fig. 7, thereby firmly attaching the molding 18 to the panel 12 either in position against the stile or crossrail or where a decorative panel effect is desired in the central portion of the panel 12, a 5 molding 20 is provided which has the contiguous portion 19 to the panel 12 so that it may be spot welded along said contiguous portion 19 of the molding 20 thereby firmly attaching the molding 20 to the panel, as 10 15 shown in Figs. 1 and 2.
- In order to decorate both sides of the door where both sides are exposed, this simple form of sheet metal door construction may be used by providing a molding 21 which 20 has the bend 19 which fits contiguously against the side of the panel 12 opposite the portion 19 in the molding 18, and the three thicknesses of sheet metal plate may be spot welded together thereby covering 25 the joint on both sides of the door in a permanent and durable manner. The molding 21 gives a flush panel effect on one side of the door, while the molding 18 gives a sunken panel effect on the other, thereby 30 giving a pleasing appearance to both sides of the door so that it can be used in a great many places where such a door constructed at low cost yet of strong fireproof construction is desired.
- 35 It is apparent that the panel 12 can be cut from the flat sheet as it comes from the rolls and be used without additional manipulation or preparation. The frame of tubular stiles and crossrails as well as the 40 molding can be drawn through suitable dies from the flat strip and cut to length for spot welding attachment, and the ornamentation is accomplished without additional work on panel, frame or molding, the parts 45 being so shaped that the attachment is made without clip or rivet nor by either of the edges of the molding. The molding usually has three points of contact, the central lengthwise welding curve and both edges. 50 Neither of the edges are used for attaching purposes so that the means of attachment is invisible and there is no cleaning or prep-

aration of the edges necessary for the finish or enamel.

I claim as new:—

1. In a sheet metal structure, a plate, molding having inturned edge portions engaged with the plate leaving space between the body of the molding and the plate, said molding having a longitudinal part in its body depressed to extend inwardly to engage the plate at points between said inturned edges of the molding, and means to secure said inwardly extended part of the molding to the plate. 55

2. In a sheet metal structure, a plate, molding having inturned edge portions engaged with the plate leaving space between the body of the molding and the plate, said molding having a longitudinal part in its body depressed to extend inwardly to engage the plate at points between said inturned edges of the molding, and said inwardly extending depressed part of the molding being welded in spots to the plate at spaced intervals throughout the length of the depressed part. 60

70 75 80 85 90 95

3. In a sheet metal structure, a tubular rail having inturned abutting flanged edges, a plate engaged with one of the flanges, molding having inturned edges engaged with the other flange and with the adjacent face of the plate, and second molding engaged with the opposite face of the plate, each molding having a lengthwise depressed part which engages the opposite faces of the plate at points opposite to each other and at points between the molding edges, and means to secure said lengthwise parts simultaneously to the plate.

4. In a sheet metal structure, a plate, and oppositely disposed moldings on the plate, said moldings having inturned edges which seat on the plate and having depressed lengthwise parts which contact with the plate on the opposite side faces of the latter, and means to secure said depressed parts simultaneously to the plate.

In testimony whereof I have affixed my signature in the presence of two witnesses.

OTHO M. OTTE.
